UNITED STATES PATENT OFFICE.

PHILIP K. STERN, OF NEW YORK, N. Y.

SALT-CARTRIDGE.

1,087,469.

Specification of Letters Patent. Patented Feb. 17, 1914.

Application filed August 28, 1912. Serial No. 717,449.

To all whom it may concern:

Be it known that I, PHILIP K. STERN, a citizen of the United States, residing in the city of New York, in the county and 5 State of New York, have invented certain new and useful Improvements in Salt-Cartridges, of which the following is a specification.

My invention in salt cartridges relates to 10 a package containing salt, which is provided with means for protecting the salt from becoming attacked by moisture. It has more particular reference to packages of this character sealed in a paper envelop 15 of suitable hard cardboard with an exterior wall, whereby a jacket of air is maintained between the envelop and the said exterior wall.

The object of the invention is to provide 20 a salt package or cartridge conducive to sanitation, which, at the same time may be placed upon the market at such a low price, that, after the contents thereof have become exhausted, the container or package 25 may be thrown away.

Another object of my invention is to provide a receptacle for the container which may be adapted to the ready insertion and withdrawal of the container therefrom, 30 while at the same time the whole may be employed as a shaker.

The features of my invention whereby I attain these objects lie in the construction 35 as disclosed in the drawings hereto attached, which, when taken with the correlative appended descriptive matter forms part of this specification, and the distinct features of novelty are referred to in the claims at the conclusion of the specification.

With reference to the drawings: Figure 1 40 is a sectional elevational view of one of my improved salt cartridges and container on a somewhat enlarged scale. Fig. 2 is a top plan view thereof. Fig. 3 is a side elevational view of one of my improved cartridges together with a sectional elevational view of a modified form of shaker, and Fig. 4 is a 45 similar view to that of Fig. 1, illustrating still another modification of the shaker.

In the several figures, similar characters of reference designate like or the same parts 50 wherein—

A refers to a cartridge or container which is preferably constructed of paper tubing 55 and is of cylindrical form.

2^a designates the bottom cover therefor of

similar material and 1^a the top perforated cover which permits the salt contained within to escape through a series of perforations a.

To normally close the perforations a, I provide a paper disk C of a diameter sufficient to cover the perforated portion of the cap 1^a, and around the margin thereof, apply an adhesive, such for example as gum or glue, whereby the rim c of this adhesive will be distributed around the edge of the disk C. Projecting from the disk C is a tab 1^c, and where the same projects from the disk C, leave an ungummed space 1^d. The application of the disk C to the cap 1^a is effected by moistening the rim c and applying the disk thereto in a familiar manner. It will be understood that inasmuch as that the disk C is secured merely around the edge to the cap 1^a, contact between the remaining portion of the disk and the said cap is obviated, thus moisture in the atmosphere is screened from the cap 1^a and the perforations a therein.

In order to screen the moisture from the outer wall of the tube A, I secure an outer tube or label 1^b by its opposite ends or edges to the outer annular wall of the cap 1^a and bottom 2^a respectively, whereby, the same 85 will be disposed as a moisture screen about the salt and tube A leaving therebetween an annular air space 1^e.

The cartridge entire, consisting of the tube A, end caps 1^a and 2^a, end cover or 90 disk C and moisture screen 1^b is inserted in a shaker for convenient use comprising an annular shell or tube B, having an integral end 1^b, provided with an annular opening b, and a flanged cover 2^b, provided with a 95 screw thread 3^b, whereby the bottom may be expeditiously removed for renewing the cartridges or containers when the same have become exhausted of their salt supply.

In the modification of Fig. 4, I have 100 shown the reverse arrangement for the opening of the shaker B, and in this instance the upper end is rendered removable in lieu of the bottom. I have also shown in this construction, the upper edge turned in so 105 as to form a sort of counter-sunk opening referred to as 2^b. I have furthermore shown a means in this construction of maintaining a contact between the upper cap 1^a and the upper end of the shaker which I accomplish 110 by placing a bow or elliptic spring 3^b in the bottom of the shaker and placing the

container or cartridge thereon, whereby the same will be pressed up against the annular edge of the cover 2^B of the shaker.

In the construction illustrated in Fig. 3
5 I provide the spring 3^B, the ends of which are carried in an annular groove 4^B of the cover 2^B.

To permit of the exit of the salt through the perforations *a*, the disk C may be re-
10 moved by grasping the tab 1^C and tearing the former from the end 1^A of the cartridge, or as an alternative when it is desired to retain the disk C as a moisture screen for the end 1^A of the cartridge, it may be perfor-
15 rated with a pin or other suitable pointed instrument through perforations *a*, and to provide an index of location, the disk C after being assembled and secured to the cap 1^A is marked over the perforations *a* by the application of sufficient pressure to the cap 1^A and the disk C in a suitable press.

It will be observed by the above description of my invention that a simple and inexpensive salt package is provided, having
25 protection against ingress of moisture from the atmosphere, together with a receptacle for protecting the moisture screen against damage as well as a means for preventing the accumulation of salt between the shaker and the container.

Having fully described my invention, I claim as new and desire to secure by Letters Patent of the U. S.

1. A salt cartridge and shaker comprising, an outer casing of moisture resisting material, having an opening at one end and closed at the other end thereof, and an

inner casing consisting of a tube of paper provided with flanged caps of paper cov-
40 ering each end of the tube, a cylindrical screen secured to the flanged portion of each of said caps and surrounding said tube of paper and forming an annular air jacket between said paper tube and screen, and a paper disk provided with a series of perfor-
45 ations, said disk being secured around its edge or rim portion to the upper surface of the upper cap and having a tab extending therefrom.

2. A salt cartridge and shaker comprising, an inner casing having a top or cover provided with a series of openings for the egress of salt, and an outer casing of moisture resisting material, having an opening at one end and closed at the other end, said 55 outer casing being provided with a counter-sunk opening in its upper end terminating in an annular depending edge, and a bow-shaped spring resting on the bottom of the outer casing, the upper central portion of 60 said spring being adapted to contact with the lower surface or bottom of the inner casing and press the inner casing upward so that the top thereof will contact with and rest against the said annular depending 65 edge of the said outer casing.

In testimony whereof, I have signed my name to this specification in the presence of two subscribing witnesses.

PHILIP K. STERN.
